SPACER MEANS FOR DUAL WHEELS

Frederick W. Burger, Niles, Mich., assignor to
 Clark Equipment Company, Buchanan, Mich.,
 a corporation of Michigan

Application December 22, 1932, Serial No. 648,423

11 Claims. (Cl. 301—12)

The present invention relates generally to wheels for automotive vehicles and the like, particularly dual rimmed wheels upon which two pneumatic tires are adapted to be mounted. Specifically, the present invention contemplates an improved spacer means to be used on dual wheels so as to maintain the two pneumatic tires in the proper laterally spaced relation with respect to the central plane of the wheel.

More particularly, the present invention is in the nature of an improvement upon the spacing means disclosed in my prior Patent No. 1,901,629, issued March 14, 1933, in which the spacing means disclosed is in the form of a spacing ring having central resilient portions to permit of a limited amount of lateral movement of the rim contacting portions in an axial direction so that when the rim clamping means was tightened the spacing means was brought to the proper position relative to the spider or wheel body on which the rims were mounted. Specifically, the particular type of spider or wheel body upon which the spacing means was adapted to be mounted is that disclosed in my prior Patent No. 1,829,889, dated November 3, 1931, in which the wheel body is provided with shoulders or abutments on the ends of the spokes. On each side of these shoulders is the spacing means mentioned above and the yielding of the resilient proportions thereof permitted the rim contacting portions of the spacing means to move into abutting engagement with the shoulders, thereby positively and accurately aligning the rims when the clamping means was tightened to force the rims against the spacing means and the spacing means against the shoulders on the wheel spider.

The spacing means of the present invention is likewise adapted to be used on a spider or wheel body of this type. One of the principal objects of the present invention is a provision of spacing means which, instead of being in the form of a continuous ring, is in the form of the plurality of segments or arcuate sections, one being provided for each spoke end in the case of felloe-less wheels. Each of the segmental spacers or spacing blocks is provided with marginal rim contacting portions and resilient central portions to provide for the relative movement of the rim contacting portions to allow the tangs or lips formed on the laterally inner portions of the latter to engage the abutment shoulders on the associated spoke end. While I have referred to felloe-less wheels, it is to be understood that my invention is not to be limited to this particular type of wheel.

Another object of the present invention is the provision of means in the form of lugs or projections carried by the rim contacting marginal portions of the spacer blocks for the purpose of initially aligning the rims.

These and other objects of the present invention will be apparent to those skilled in the art after a consideration of the following detailed description of the construction in which the principles of the present invention are preferably embodied.

The preferred construction is illustrated in the accompanying drawings, in which:

Figure 1 is a perspective view of a spoke end with the spacer block disposed in operative position thereon, certain parts being shown in section to better illustrate the relations involved;

Figure 2 is a transverse section taken through the construction shown in Figure 1;

Figure 3 is a top plan view of one of the spacer blocks;

Figure 4 is a side view of the spacer block shown in Figure 3; and

Figure 5 is an enlarged fragmentary view corresponding to a section taken along the line 5—5 of Figure 3 and showing the function and operation of the preliminary aligning lug means formed in the mid portion of each of the rim contacting marginal flanges of the spacer block.

Referring now to the drawings, the reference numeral 1 indicates the radially outer portion of a spoke of a felloe-less wheel. The spoke end is formed with an inboard socket 2 on each side of which is a seat or ledge 3 adapted to receive a clamping lug 4 of wedge formation, the clamping lug being provided with an apertured ear 5 arranged to be received within the socket 2 and embracing the head end 6 of a clamping bolt 7 extending from one side of the spoke end to the other.

The two rims adapted to be mounted in dual relation on the wheel are indicated by the reference numerals 11 and 12, the rim 11 being the inboard rim while the other rim 12 is the outboard rim. Each of the rims are of the type which are provided with a gutter 14 for receiving the removable flange 15 of the rim. This type of rim has the gutter portion 14 thereof formed with a tapered clamping or wedge surface 17 which faces radially inwardly of the rim and which is of an angularity corresponding to the angularity of the wedge-shaped clamping lugs 4, as best shown in Figure 2.

The ledges or seats 3 of the wheel are disposed in a cylindrical surface, the diameter of which

is slightly less than the smallest diameter of the rims 11 and 12. This allows the inboard rim to be slipped over the ends of the spoke to its proper position on the inboard side thereof.

- 5 The radially outer end portion of the spoke 1 is provided with central abutment means in the form of integral shouldered projections 25 which provide a circumferential series of centrally disposed abutments which are accurately disposed 10 and dimensioned with respect to the central plane of the wheel body. The shoulders 26 provided by the projections 25 form a part of the means for accurately aligning the rims on the wheel body. In accordance with the principles 15 of the present invention there is provided for each spoke end a form of spacing means which cooperates with the shoulders 26 and the adjacent marginal portions 14 of the rims whereby the latter are accurately disposed on the wheel 20 body in the proper position.

The spacer block of the present invention comprises a segmental or arcuate section of flat metal stock having marginal flanges 31 joined to the main body of the spacer block by sections 25 32 which are arcuate in cross section and which are adapted to have line contact with the adjacent or inner edges 14 of the rims. The arcuate portions 32 merge into substantially flat sections 34 which are adapted to be disposed on 30 opposite sides of the central spoke abutments 25. These oppositely disposed sections terminate inwardly in tangs or lips 35 which contact directly with the shoulders 26 on the spoke end. The ends of the sections 34 are joined by resilient portions 40 which are arched radially inwardly of the wheel and which are resilient to provide for limited relative movement between the lateral sections 34 carrying the marginal flanges 31 and the tangs or lips 35. The outboard section 34 is slit, as at 43, and a section 44 turned radially inwardly and apertured to provide a 40 tongue to receive the bolt 7 for the purpose of preventing the spacer block from slipping out and becoming lost. Also, as best shown in Figure 1, the end portions 40 of the spacer contact 45 with portions of the spoke and keep the spacer in proper position on the wheel.

The construction of the clamping lugs 4 are 50 preferably that disclosed in my prior patent mentioned above. The inboard clamping lugs 4 have been referred to above. The outboard clamping lug is indicated by the reference numeral 50 in Figure 2 and includes an apertured ear portion 51 movable in an outboard socket 52 formed 55 in the spoke end. The outboard end of the clamping bolt 7 is threaded, as at 54, to receive a clamping nut 55 which is adapted to bear against the lug 50. Tightening the nut 55 draws the lugs 4 and 50 against the rims 11 and 12, respectively, the adjacent margins 14 thereof engaging the flanges 31 on the spacer block. Continued tightening of the nut 55 acts through the rims 11 and 12 to shift the lateral sections 34 of the spacer block inwardly toward and into engagement with the shoulders 26 on the spoke end. Each of the clamping lugs 4 and 50 are provided with inwardly disposed shoulders or tangs 60 and 61 which, as disclosed in my prior patent, provide for initially centering the rims in approximately the proper position. To cooperate with the tang sections 60 and 61 on the clamping lugs, the spacer block is provided with laterally outwardly directed lug means 65 to initially engage with the edge or gutter portion 14 of each rim to bring the same to approximately its posi-

tion on the wheel. Preferably, these lug portions are formed integrally with the spacer block. For example, the lugs 65 may be formed by projecting or pressing a portion of the material at the mid-section of the marginal flanges 31 and 32, as indicated in Figures 3 and 5.

While I have shown and described above the preferred construction in which the principles of the present invention are preferably embodied, it is to be understood that my invention is not 10 to be limited to the specific means shown and described, but, that in fact, widely different means may be employed in the practice of the broader aspects of my invention.

What I claim, therefore, and desire to secure 15 by Letters Patent is:

1. In a dual rimmed wheel having spokes and rim clamping means at the radially outer ends thereof, a plurality of spacer blocks adapted to be disposed between the rims of the wheel and 20 in contact with said rims, each spacer block being disposed adjacent the outer end of the associated spoke and on opposite sides of a portion thereof, the reaction of said clamping means 25 acting to force opposite portions of said spacer block against opposite side portions of said spoke end, each spacer block including portions engageable with the ends of the associated spoke to keep the block in proper position thereon.

2. In a dual rimmed wheel having spokes and rim clamping means at the radially outer ends thereof, a spacer member adapted to be mounted on a spoke end and between the rims on the wheel, said member having an open central portion arranged to embrace at least a portion of 35 the spoke end and resilient portions providing for movement of opposite sections of said member relative to each other and into abutting engagement with portions of the spoke end under the action of said clamping means, and means carried by the ends of the spacer member to prevent the latter from turning relative to the axis of the spoke end on which the member is mounted.

3. In a dual rimmed wheel having spokes and rim clamping means at the radially outer ends 45 of the spokes for clamping the rims on the wheel, a spacer member adapted to be mounted on each spoke end and between said rims, each spacer member having a radially outwardly disposed marginal flange at the side edges thereof, an 50 open central portion arranged to embrace at least a portion of the spoke end, lips projecting inwardly of the open central portion from opposite sides thereof and adapted to engage opposite portions of the spoke end, arched resilient sections at the ends of said open central portion and disposed on opposite sides of the spoke in a circumferential direction, the resiliency thereof permitting said lips to approach each other and to abut against said opposite portions of the 60 spoke end when the rims are clamped against said marginal flanges by said clamping means, and an attachment means carried by the spacer member and engageable with at least a portion 65 of said clamping means for retaining said member in position on the spoke end.

4. In a dual rimmed wheel having spokes and means at the radially outer ends of the spokes for clamping the rims on the wheel, a spacer member adapted to be mounted on each spoke 70 end and between said rims, each spacer member having a radially outwardly disposed marginal flange at the side edges thereof, an open central portion arranged to embrace at least a portion of the spoke end, lips projecting inwardly of the 75

- open central portion from opposite sides thereof and adapted to engage opposite portions of the spoke end, radially inwardly arched resilient sections at the ends of said open central portion, 5 the arched sections being spaced apart circumferentially of the wheel so as to be disposed on opposite sides of the spoke end in a circumferential direction, the resiliency thereof permitting said lips to approach each other and to abut against said opposite portions of the spoke end when the rims are clamped against said marginal flanges by said clamping means, and an integral attaching apertured ear extending radially inwardly from one of said lips and adapted to embrace said bolt means to secure the spacing member in position on the spoke end. 10
5. In a dual rimmed wheel having spokes and rim clamping means at the radially outer ends thereof, a plurality of spacer blocks adapted to be disposed between the rims of the wheel and in contact with said rims, each spacer block being disposed adjacent the outer end of the associated spoke and on opposite sides of a portion thereof, the reaction of said clamping means 15 acting to force opposite portions of said spacer block against opposite side portions of said spoke end, and means on each block for initially centering the rims as said clamping means are tightened. 20
- 30 6. A spacer block adapted to be disposed between the rims of a felloe-less dual rimmed wheel, said spacer block comprising a segmental section having upturned marginal flanges adapted to contact with the adjacent portions of the rims and downturned end portions spaced in a circumferential direction and adapted to engage opposite outer sides of a spoke end of the wheel, said downturned end portions being resilient to accommodate relative movement between said rims while maintaining the spacer block in proper position on the associated spoke end during said relative movement. 25
- 35 7. A spacer block adapted to be disposed between the rims of a felloe-less dual rimmed wheel, said spacer block comprising an arcuate segmental section having upturned marginal flanges having portions arcuate in cross section and adapted to have substantially line contact with the adjacent edges of the rims, and means on each block for initially centering the rims as said clamping means are tightened, said means comprising a lug projecting laterally outwardly from the mid portion of each of said marginal flanges. 40
- 45 8. Spacer means adapted to be disposed between the rims of a felloe-less dual rimmed wheel and comprising a pair of relatively movable sections each having at its laterally outer edge an
- upturned marginal flange adapted to contact with the adjacent portion of the associated rim, and means near the end portions of said sections and cooperating with the spoke end for holding the spacer means in approximately proper position. 5
9. In a dual rimmed wheel having spokes and rim clamping means at the radially outer ends of the spokes for clamping the rims on the wheel, a spacer member adapted to be mounted on each spoke end and between said rims, each spacer member having marginal sections with a radially outwardly disposed marginal flange at the side edges thereof, an open central portion arranged to embrace at least a portion of the spoke end, said marginal sections being adapted to engage opposite portions of the spoke end, and arched resilient sections at the ends of said open central portion and disposed on opposite sides of the spoke in a circumferential direction, the resiliency thereof permitting said marginal sections to approach each other and to abut against said opposite portions of the spoke end when the rims are clamped against said marginal flanges by said clamping means. 10
10. In a dual rimmed wheel having spokes and rim clamping means at the radially outer ends of the spokes for clamping the rims on the wheel, a spacer member adapted to be mounted on each spoke end and between said rims, each spacer member having marginal sections with a radially outwardly disposed marginal flange at the side edges thereof, an open central portion arranged to embrace at least a portion of the spoke end, said marginal sections being adapted to engage opposite portions of the spoke end, and connecting means joining said marginal sections, said connecting means being disposed on opposite sides of the spoke in a circumferential direction and in contact therewith, and said connecting means being arranged to permit said marginal sections to approach each other and to abut against said opposite portions of the spoke end when the rims are clamped against said marginal flanges by said clamping means. 15
11. A spacer block adapted to be disposed between the rims of a felloe-less dual rimmed wheel, said spacer block comprising a section having marginal portions adapted to contact with the adjacent portions of the rims, and resilient end portions spaced in a circumferential direction relative to the wheel and adapted to engage opposite outer sides of a spoke end of the wheel for the purpose of accommodating relative movement between said rims while maintaining the spacer block in position on said spoke end. 20
